GUSSET TYPE BAG

Richard E. Adams, Hightstown, N. J.

Application March 1, 1954, Serial No. 413,158

6 Claims. (Cl. 229—54)

This invention relates to bags formed of paper or the like and is directed particularly to gusset type bags wherein there are front and rear panels connected by side members which are centrally creased and project inward between the front and rear panels when the bag is closed.

Gusset type bags are frequently used in packaging and shipping produce such as potatoes, apples and the like, although they have many other uses. Such bags are frequently stitched across the top or the front and rear panels may be stapled together at the top of the bag to hold it closed and prevent spilling of the contents. However, stitched or stapled bags cannot be reclosed readily or effectively after they have once been opened. It is also desirable to provide such bags with a handle opening to enable the bags to be carried about and handled easily. When such a handle opening is provided the portion of the front and rear panels which are cut to form the opening frequently constitute retaining flaps which serve to hold the front and rear panels of the bag together to afford a retaining means which can be moved to permit opening of the bag for inspection while allowing the bag to be reclosed. On the other hand, when such a handle opening is provided, the gussets at the side of the bag are not held securely in place between the front and rear panels with the result that the gussets may open under load or when the bag is handled roughly, permitting the contents to spill or causing tearing of the bag.

In accordance with the present invention, these objections to prior gusset type bags are overcome and means are provided which afford a handle opening while serving to prevent displacement of the gusset whereby the top of the bag is held firmly closed even though the bag is subjected to severe usage. This result is preferably attained by forming a handle opening near the top of the bag and further providing means on the gussets which may extend through the handle opening to prevent undesired lateral displacement or opening of the gussets even when the bag is closed.

One of the objects of the present invention is to provide a novel gusset type bag having means for preventing displacement of the gussets when the bag is closed.

Another object of the invention is to provide gusset type bags having a novel type of construction adjacent the top thereof.

A specific object of the invention is to provide gusset bags with a handle opening and retaining means which are connected to the gussets and serve to prevent displacement of the gussets when the bag is closed.

These and other objects and features of the present invention will appear from the following description thereof in which reference is made to the figures of the accompanying drawing.

In the drawing:

Fig. 1 is a perspective showing a portion of a typical form of gusset type bag embodying the present invention;

Fig. 2 is a perspective showing the construction of Fig. 1 with the top of the bag expanded before closing;

2

Fig. 3 is a perspective illustrating the position of certain elements of the construction shown in Fig. 1 when in partially closed position; and

Fig. 4 is a perspective illustrating an alternative form of the present invention.

In that form of the invention chosen for purposes of illustration in Figs. 1, 2 and 3, the bag is provided with a front panel 2 and a rear panel 4 connected at their edges to the side members or gussets 6 and 8 which consist of centrally creased inwardly extending portions of the material of which the bag is formed. The upper portion of the front and rear panels are preferably reinforced with cardboard or other stiffening material as indicated at 10. Further, if desired, the inner edge portions 12 of the gussets 6 and 8 may be provided with a strip of reinforcing material 14 extending lengthwise of the crease in the upper portion of the bag.

The bag is provided with a handle opening 16 in the upper portion thereof which is formed as indicated in Fig. 2 by a cut 18 which defines the top and ends of the handle opening 16, and at the same time, defines the arcuate edge of the retaining flaps 20. In the preferred form of the invention shown in Figs. 1, 2 and 3, the front and rear of the bag are further provided with relatively small openings 22 which are formed in the front and rear panels of the bag in a position to be located adjacent the lower edge of the downwardly turned retaining flaps 20. A wire or tie device 24 may be applied so as to extend through the handle opening 16 and the smaller openings 22 with the ends tied or twisted as shown in Fig. 1 to hold the retaining flaps 20 in their downwardly closed bag retaining position.

The construction so far described is essentially the same as that of my copending application Serial No. 348,427 filed April 13, 1953. However, in accordance with the present invention, the handle opening 16 is of such width that it extends beyond the inner edges 12 of the gussets 6 and 8. The cut 18 defining the handle opening is preferably formed in the bag or bag forming material while the gussets are in their creased and turned positions whereby the formation of the cuts 18 further serves to form the arcuate cuts 24 which extend inwardly and downwardly in the creased edges 12 of the gussets. In this way arcuate tabs 26 are formed which lie between the retaining flaps 20 formed in the front and rear panels 2 and 4. The tabs are located adjacent the opposite ends of the retaining flaps and upon downward folding of the retaining flaps, the tabs 26 are folded over and downward between the retaining flaps and are positively gripped and held in position so that the gussets are secured in place and cannot move outward to expand and open the mouth of the bag. As shown diagrammatically in Fig. 3, the portions of the front and rear panels of the bag which constitute the ends of the retaining flaps 20 lie on opposite sides of the arcuate tab 26 and the tab as well as the retaining flaps are folded over when the retaining flaps are bent downward to bag closing position. This lateral displacement of the tab 26 sideways through the handle opening affords a positive retaining and locking means which precludes outward movement of the creased inner edge 12 of the gusset. The gusset cannot pull sideways from between the front and rear panels without actually tearing out the tab. Moreover, the outward strains tending to cause the bag to open are normally exerted from the interior of the bag by the produce therein which, in turn, serves to prevent downward tearing of the tab with the result that no actual tearing has been found to take place even though the bags are inverted and vigorously shaken. Nevertheless, the creased portions of the gussets along the inner edges 12 may be reinforced as indicated at 14 if desired. Further, if such reinforcing means are

70

provided in the form of soft metal strips, the lateral bending of the tabs into bag retaining position may be sufficient in itself to hold the retaining flaps 20 in their downwardly folded position. In that event, the tie wire 24 may not be necessary.

The construction illustrated in Fig. 4 is generally similar to that of Fig. 3, but the handle opening is formed with retaining flaps 30 which may be folded upward adjacent the upper edges of the bag. If desired, a tie wire may be employed and extend through the handle opening and about the upper edge of the bag. However, as shown, the retaining flaps 30 are secured in place by means of a staple 34. The construction of Fig. 4, like that of Figs. 1, 2 and 3 embodies a handle opening which extends beyond the inwardly folded edges of the gussets 36. In this way the arcuate locking tabs 38 are provided and are folded sideways with the retaining flaps 32 whereby outward displacement of the gussets is positively prevented.

In each of the forms of the invention shown, the front and rear panels of the bag are held in gripping engagement with the gussets whereas the gussets themselves are formed with locking tabs which are bent sideways so that the gussets are positively held in closed position and are secured against displacement. Bags of this character, therefore, can be subjected to severe usage and abuse without danger of displacement of the gussets or loss of the articles from the bag. Furthermore, the gripping of the gussets prevents accidental or undesired opening whereby tearing or mutilation of the bag about the handle opening is prevented.

Those forms of the invention which have been chosen for purposes of illustration are cited as typical of the many and various constructions and arrangements which may be employed in the practice of the present invention. However, numerous other and alternative constructions and modifications of the invention may be made. In view thereof, it should be understood that the particular embodiments of the invention shown in the drawing and described above are intended to be illustrative only and are not intended to limit the scope of the invention.

I claim:

1. A bag having front and rear panels connected at their opposite edges by side members which are centrally creased and extend inwardly between said panels as gussets when the bag is closed, the upper portions of the front and rear panels of the bag having registering handle openings therein, said handle openings extending beyond the creased edges of said gussets and said gussets having cuts formed therein providing locking tabs movable through said openings to prevent lateral displacement of the gussets.

2. A bag having front and rear panels connected at their opposite edges by side members which are centrally creased and extend inwardly between said panels as gussets when the bag is closed, the upper portions of the front and rear panels of the bag having registering handle openings therein, said handle openings extending beyond the creased edges of said gussets and said gussets having cuts formed therein providing locking tabs movable through said openings to prevent lateral displace-

ment of the gussets, and retaining flaps carried by said front and rear panels and movable through said handle openings with said locking tabs therebetween to hold the panels and gussets in bag closing position.

5. A bag having front and rear panels connected at their opposite edges by side members which are centrally creased and extend inwardly between said panels as gussets when the bag is closed, the upper portions of the front and rear panels of the bag having registering handle openings therein, said handle openings extending beyond the creased edges of said gussets and said gussets having cuts formed therein providing locking tabs movable through said openings to prevent lateral displacement of the gussets, and retaining flaps carried by said front and rear panels and movable through said handle openings with said locking tabs therebetween to hold the panels and gussets in bag closing position, and means for holding said retaining flaps in bag closing position.

20 4. A bag made of paper and having front and rear panels connected at their opposite edges to side members which are creased centrally so as to fold inward between the panels in the form of gussets when the bag is closed, the upper portion of the front and rear panels being reinforced and stiffened, the panels having cuts formed in 25 the stiffened portions thereof defining registering handle openings which extend at their opposite ends beyond the inner edges of the gussets when the bag is closed, the portions of said panels outlined by said cuts constituting retaining flaps and being foldable together through the 30 handle openings to positions in which they are parallel to the outer face of one panel, the portions of said gussets which are positioned between said retaining flaps being formed with cuts registering with the cuts in the front and rear panels and defining locking tabs which 35 are foldable with said retaining flaps through said handle opening and into position to prevent lateral displacement of the gussets when the retaining flaps are in said folded position.

40 5. A paper bag of the character defined in claim 4 wherein the creased edges of the gussets are reinforced in the area thereof which defines the locking tabs.

6. A paper bag of the character defined in claim 4 wherein the retaining flaps are foldable downward below 45 the handle opening and the front and rear panels have registering openings therein positioned adjacent the downwardly folded retaining flaps, and a fastening strip extending through the latter openings and the handle openings and serving to hold the retaining flaps and locking tabs in said folded position.
